UNITED STATES PATENT OFFICE.

DONALD J. VANDYKE, OF CAMBRIDGE, MASSACHUSETTS, ASSIGNOR OF ONE-HALF TO
JOSEPH SHAIN, OF CAMBRIDGE, MASSACHUSETTS.

CONTAINER.

1,104,852.

Specification of Letters Patent. Patented July 28, 1914.

Application filed August 20, 1913. Serial No. 785,811.

To all whom it may concern:

Be it known that I, DONALD J. VANDYKE, a citizen of the United States, residing at Cambridge, in the county of Middlesex and 5 State of Massachusetts, have invented certain new and useful Improvements in Containers; and I do hereby declare the following to be a full, clear, and exact description of the invention, such as will enable 10 others skilled in the art to which it appertains to make and use the same.

My invention relates to paper containers adapted to contain liquids such as milk, syrups etc. and to be thrown away or destroyed after single usage.

An important object of my invention resides in the provision of a container which may be folded to take up little space when shipped in bulk in folded position and one 20 materially strengthened by reinforcing strips arranged crosswise at the bottom thereof.

Another object of my invention is to provide a container of the above mentioned 25 character which, owing to its peculiar construction may be packed for shipment with the liquid therein contained in a compact and rigid manner and consuming little space.

30 Another object of importance is to provide an efficient lid or cover for the receptacle which may be readily removed therefrom owing to its construction and arrangement.

35 A still further object of my invention is to provide a container of the above mentioned character which may be cheaply manufactured as it is simple as to construction and arrangement and one which will be 40 clean and sanitary owing to the fact of its single usage.

The above and additional objects are accomplished by such means as are illustrated in the accompanying drawings, described 45 in the following specification and then more particularly pointed out in the claim which is appended hereto and forms part of this application.

With reference to the drawings, wherein, 50 I have illustrated the preferred embodiment of my invention as it is reduced to practice, and throughout the several views of which, similar reference numerals designate corresponding parts.

55 Figure 1 is a perspective view illustrat-

ing my device in assembled position and ready for containing the liquid, Fig. 2 is a view of my device in its folded position, Fig. 3 is a top plan view illustrating the cap in closed position, Fig. 4 is a bottom 60 plan view illustrating the reinforcing strips secured to the container, and Fig. 5 is a vertical sectional view illustrating the manner of securing the mouth piece to the container also the manner of securing the lid 65 or cover to the mouth piece.

Referring now to the drawings the container consists of a conoidal body portion designated 1 as an entirety provided with usual side walls 2 and bottom wall 3 which 70 is preferably constructed of paper but may be constructed of any suitable fibrous material and made impervious by a coating of paraffin or other suitable material non-injurious to the liquids to be contained in the 75 container. The upper or neck portion 4 of the body portion 1 is of a cylindrical shape to facilitate the mounting of the mouth piece after the manner which will be hereinafter more fully described. 80

As a means for stiffening the structure, as such means is necessary owing to the large containing area at the base of the body portion 1, there has been provided a pair of crossed bracing or reinforcing strips 5 which 85 are secured in any suitable manner to the bottom wall 3 of the container and are constructed of card-board or other suitable stiff material. It will thus be seen that a container is provided which, owing to its enlarged base construction, will, when filled with liquid and placed within a packing box or crate in great numbers, be wedged in engagement with each other and firmly packed. 90

An annular mouth piece 6 formed of card-board or other suitable stiff material and provided with an inwardly extending annular flange 7 at its lower terminal is mounted upon the upper cylindrical portion 4 of the body portion 1 by crimping the upper terminal of the cylindrical portion 4 in engagement with the flange 7 or by gluing it in engagement with the flange. An annular cap or lid 8 provided with diametrically opposed flaps 9 and 10 is mounted within the mouth piece 6 pressed in engagement with the flange 7 formed thereon to provide the sealing action. The flap 10 is bent about the adjacent portion of the mouth piece 6 and secured thereto by an adhesive 105 110

or other suitable fastening means to provide a hinge connection and the flap 9 is arranged to extend upwardly from the cap 8 when the cap is inserted within the mouth piece, so 5 that it may be readily engaged by the fingers to lift the flange from sealing engagement with the flange 7 to pour the contents of the bottle therefrom.

When it is desired to ship an article, such 10 as has been described, in bulk, the bottom wall 3 is folded to lie against one of the side walls 2 in vertical alinement therewith and it will thus be seen that great numbers of containers may be packed when so folded.

15 In reduction to practice, I have found that the form of my invention, illustrated in the drawings and referred to in the above description, as the preferred embodiment, is the most efficient and practical; yet realizing 20 that the conditions concurrent with the adoption of my device will necessarily vary, I desire to emphasize the fact that various minor changes in details of construction, proportion and arrangement of parts may be

resorted to, when, required, without sacrificing any of the advantages of my invention, as defined in the appended claim.

What is claimed is:

The combination with a foldable container having a cylindrical neck, an annular mouth piece, an inwardly extending peripheral flange on the mouth piece adjacent the lower face thereof, said mouth piece being rectangular in cross section, the upper edge of said neck being bent over at right angles to the neck and secured to the upper face of the flange, and a closure cap for the container adapted to fit within the mouth piece and engage the bent over edges of the neck of the container when in sealing engagement with the container.

In testimony whereof I affix my signature in presence of two witnesses.

DONALD J. VANDYKE.

Witnesses:

JOHN AMEE,
MARGARET L. SMITH.
